UNITED STATES PATENT OFFICE.

ALFRED SPRINGER, OF CINCINNATI, OHIO, AND WILLIAM KENT, OF JERSEY CITY, NEW JERSEY.

GRAIN-METER.

SPECIFICATION forming part of Letters Patent No. 365,876, dated July 5, 1887.

Application filed November 24, 1886. Serial No. 219,841. (No model.)

To all whom it may concern:

Be it known that we, ALFRED SPRINGER and WILLIAM KENT, citizens of the United States, residing at Cincinnati, Ohio, and Jersey City, New Jersey, respectively, have invented new and useful Improvements in Grain-Meters, of which the following is a specification.

Our invention relates to scales or meters for the automatic determination of measures of grain, &c., and is intended, primarily, to produce a simple, durable, and accurate mechanism for the purpose indicated, whereby grain in a continuously-descending stream is received by suitable receptacles in predetermined quantities, and acts by gravity to discharge itself and operate the mechanism by regular, recurring, and registrable movements in fixed relations to the quantities of grain delivered.

In the present invention we make use of the general principle of shifting the center of gravity of an oscillating apparatus maintained constantly above the axis of rotation alternately to opposite sides of the perpendicular plane of such axis by means of the grain accumulating in suitably-arranged receptacles. The general operative principle of such apparatus is old; but as heretofore constructed the oscillating apparatus was sustained upon "knife-edge" pivots, as in the common methods of scale construction, or upon journal-pivots, involving friction. The former construction is necessarily complicated and expensive, and the wear upon the knife-edge bearings soon destroys their efficiency, while the latter construction is obviously crude and inaccurate in results.

In our improvement we construct the apparatus with a torsion-pivot of oscillation, which is peculiarly adapted to the mechanical movements involved, because it acts by temporary molecular displacement within the limits of molecular elasticity, and is consequently free from the excessive wear which any form of bearing involving friction is necessarily subject in this form of apparatus. Inasmuch as the pivot in this case carries the entire weight of the apparatus, with a load constantly shifting and oscillating the apparatus, the torsion-pivot in this connection performs a pecu-

liarly useful function. Moreover, it enables us to dispense with much of the mechanism ordinarily required, and reduces the construction to the most elementary, economical, and effective form.

Mechanism embodying our invention is illustrated in the accompanying drawings, in which—

Figure 1 is a side elevation of the apparatus complete; Fig. 2, a detail showing an alternative mode of arranging the discharging gate mechanism; Fig. 3, a perspective view of the torsion-pivot frame and support with the boxes removed.

Referring now to the drawings, A, B designate two boxes, preferably of sheet metal, held in yokes formed by the bifurcated extensions *a a* of a pivoted scale-beam, C. The boxes are brought together at the top, leaving space 65 between for a weight, W, held adjustable upon a standard, *s*, rising vertically from the scale-beam centrally above the pivot. The pivotal support of the structure is a band or strip, P, of elastic metal, held in tension around a frame, D, the latter being upheld by supports *d* from a suitable base, E. The balance-beam C is shown curved upward from its central pivot-connection, the object being to assist in elevating the center of gravity of the apparatus above the axis of rotation, to which end also the poise-weight W is employed, so that the resistance of the torsion-pivot may be at all times overbalanced and the apparatus be "top-heavy" and remain depressed at one 75 side or the other. The boxes are each closed at the bottom by a hinged trap, *b*, normally held closed by a weight, *w'*, acting through a pivoted arm, *e*, and link *e*, as in Fig. 1, or attached directly upon a rear extension of the trap, as in Fig. 2. In either case, upon the depression of the box to which it is attached, the weight *w'* strikes the stop or shelf *f* and causes the trap to open below, as indicated by the dotted lines. The apparatus, being 80 overbalanced in relation to its pivotal support, remains in such tilted position until the accumulating weight of grain in the opposite compartment shifts the center of gravity to the opposite side of the vertical plane of the 85 axis of rotation. It will be seen that the first effect is to bring the balance-beam to a hori-

zontal relation, lifting the weight W to the upward limit of its arc of oscillation, passing which the weight is transferred to the descending side. The weight required to effect this movement is the unit measure of the apparatus, and may be varied by substituting a lighter or heavier weight, W , as required, and is adjustable with a given weight by elevating or depressing the same upon its stand-
ard s .

The grain is delivered to the apparatus by gravity from a spout, S , in a continuous stream, and as the tilting of the apparatus from one side to the other shifts the open tops of the boxes to alternate positions, the grain falls into the box, whose open top is immediately below it for the time being. The weights w' are just sufficient to hold the traps b closed against the weight of grain in the boxes when the latter are elevated. As they fall, the weights are arrested and the traps thrown open, allowing the grain to discharge below.

We do not in this application confine ourselves to the particular form and arrangement of the torsional pivot shown, as any form of pivot, whether round, square, flat, &c., may be used, and held upon any construction of frame or abutments capable of holding the same in tension. Experience, however, has shown that a pivot tensioned around a frame or system of struts in a substantially rectangular path is best for the purpose.

Stops t may be provided to arrest the os-

cillation of the apparatus at the proper limits. 35 Suitable recording apparatus is to be attached to register the number of oscillations.

We claim as our invention and desire to secure by Letters Patent of the United States—

1. The automatic grain-meter embodying, 40 in combination, a torsion-pivot, P , tension-frame D , balance-beam C , and boxes A B , substantially as set forth.

2. The combination, in an oscillating grain-meter, of the boxes A B , beam C , torsion-pivot P , and the adjustable weight W , substantially as set forth. 45

3. The combination, in an oscillating grain-meter, of the boxes A B , beam C , pivot P , hinged trap b , weight w' , and stops f , substantially as set forth. 50

4. The combination and arrangement, in an automatic grain-meter, of the spout S , boxes A B , adapted to oscillate in relation thereto, as shown, the pivot P and its supports, beam 55 C , hinged bottoms b , weights w' , and stops f , substantially as set forth.

In testimony whereof we have hereunto set our hands in the presence of two subscribing witnesses.
